ANTENNA

Robert W. Masters, Erlton, N. J., assignor to
 Radio Corporation of America, a corporation of
 Delaware

Application February 21, 1945, Serial No. 578,995.

8 Claims. (Cl. 250—11)

1

This invention relates to antennas, and more particularly to broad band radiator systems suitable for the transmission and reception of ultra high frequency signals covering a wide frequency spectrum, as is required for television picture transmission, certain types of radio locator systems, and so on.

The principal object of the present invention is to provide a broad band antenna structure in which the radiator elements are in the form of flat plates or sheets, shaped to provide approximately constant impedance throughout a relatively wide frequency band.

Another object is to provide an antenna system of the described type which is simple and rugged in construction and may be designed readily to fulfill typical operating requirements.

These and other objects will become apparent to those skilled in the art upon consideration of the following description with reference to the accompanying drawing, of which

Figure 1 is a schematic perspective diagram of a directive antenna embodying the instant invention,

Figure 2 is a section showing a portion of the structure of Figure 1, in detail, and

Figure 3 is an elevation of a modified form of radiator element for a system like that of Figure 1.

Referring to Figure 1, a pair of radiator elements 1 and 3 are disposed substantially at the focus of a cylindrical parabolic reflector 5. The radiators 1 and 3 are supported, as shown more clearly in Figure 2, on insulators 7 and 7' at the ends of a pair of coaxial transmission line sections 9 and 9', and are connected to the inner conductors thereof. The line sections 9 and 9' extend through the rear of the reflector 5 to a line balance convertor 11.

The balance convertor 11 is of conventional design, and includes a cylindrical sheath 13 surrounding the final quarter wavelength section of an unbalanced line 15, and connected to the outer conductor thereof by a disc 17. The inner conductor of the balanced line 9 is connected to the outer conductor of the line 15 and the inner conductor of the line 9' is connected to the inner conductor of the line 15. A compensating stub is provided, comprising a quarter wave conductor 19 connected to the sheath 13 by a disc 17' and connected at its other end to the inner conductors of the lines 9' and 15.

The radiator elements 1 and 3 are in the form of flat sheets of generally triangular or trapezoidal outline, supported with their bases paral-

2

lel and adjacent each other, lying in a common plane perpendicular to the directive axis of the reflector 5. The plane of the radiators 1 and 3 includes the focal line of the parabolic reflector 5.

In the operation of the system for transmission, radio energy is applied to the unbalanced line 15. The convertor 11 transforms the applied voltage to two equal voltages, 180 degrees out of phase with each other, which appear across the lines 9 and 9' and are applied thereby to the radiators 1 and 3.

Thus the radiators are excited as the elements of a dipole, with current flowing into the radiator 3 while an equal current flows out of the radiator 1, and vice versa.

The reflector 5 functions to direct substantially all of the radiated energy in a relatively narrow beam. Since the dimensions of the reflector are small, in terms of wavelength, the action is not closely analogous to that of a light source with an optical reflector. Some of the reflected energy induces currents in the radiators, of magnitude and phase depending upon the size and shape of the radiators, and the focal length of the reflector. These induced currents materially affect the impedance presented by the radiators to the feed system.

For efficient broad band operation of an antenna, the impedance must remain relatively constant throughout the operating band. It is known that radiators having large surface areas exhibit this characteristic to some extent. However, it is found that a closely coupled reflector will introduce considerable variation in the impedance of a conventional broad band radiator.

By employing flat sheet radiators of generally triangular shape, as described herein, the currents induced in the radiators by reflection are controlled as a function of frequency so as to partially compensate the normal variation of impedance of the radiators alone, thus providing an overall impedance which is substantially independent of frequency. The exact current distributions in the radiators of the system of Figure 1 are not known at present, but it has been found by experiment that the optimum shape for one antenna is triangular, with dimensions approximately such that the length of each radiator from apex to base is substantially equal to the width across the base, both being about one quarter wavelength at the mean operating frequency. The focal length of the reflector is approximately 0.35 wavelength.

Another antenna, of the same type but with a somewhat different proportioning of the con-

vector 11 and the line sections 9 and 9', was found to operate best with radiator elements in the form of trapezoids, or truncated triangles, as illustrated in Figure 3. In this case, the optimum dimensions were found to be approximately those shown in Figure 3. In the absence of a better generic term, the words "generally triangular" are used herein and in the appended claims to mean the shape shown in Figure 3 as well as that of Figure 1, and similar intermediate shapes which are in fact generally or approximately triangular.

In order to operate efficiently, not only must the antenna impedance be constant, but it must match that of the feed lines. While coaxial lines may be built to have any reasonable value of characteristic impedance, it is convenient to use a commercially available line, having an impedance of approximately 50 ohms. The structure of Figure 1, with the described dimensions, will match such a line. It should be noted that the line sections 9 and 9' must have a characteristic impedance half that of the remainder of the system, or in the present example, 25 ohms.

The operation of the system for reception is similar to that for transmission, and similar requirements must be met for broad band operation, although in general they are not so critical. The described antenna, if designed for transmission, will provide satisfactory characteristics for reception.

Although the invention has been described as an antenna including only a single pair of radiators and a single parabolic reflector, it will be apparent without further illustration that a plurality of such structures may be used in combination, each acting as one element of an array, without materially affecting the broad-band characteristics secured in accordance with my invention by the combination with a reflector of a flat sheet radiator of generally triangular shape.

I claim as my invention:

1. A broad band antenna including at least one pair of radiator elements comprising flat sheets of conductive material, each of approximately triangular form, lying in a common plane with their bases parallel and adjacent each other, and transmission line means connected to said radiator elements respectively at substantially the midpoints of said bases.

2. A broad band antenna including at least one pair of radiator elements comprising flat sheets of conductive material, each of approximately isosceles triangular form, lying in a common plane with their bases parallel and adjacent each other, and transmission line means connected to said radiator elements respectively at substantially the midpoints of said bases.

3. A broad band antenna including a reflector and at least one pair of radiator elements comprising flat sheets of conductive material, each of generally isosceles triangular form, lying in a common plane with their bases parallel and adjacent each other, and transmission line means connected to said radiator elements respectively at substantially the midpoints of said bases.

4. A broad band antenna comprising a reflector, a line balance convertor lying outside and adjacent the back of said reflector with its longitudinal axis parallel to the focal axis of said reflector, a pair of balanced lines extending parallel to each other and perpendicular to said axes from said convertor, and a pair of coplanar sheet radiator elements connected to and supported by said balanced lines respectively, said sheet radiator elements being of approximately triangular form, with their bases parallel and adjacent each other at the points of connection to said balanced lines.

5. A broad band antenna comprising a cylindrical parabolic reflector, a line balance convertor of generally cylindrical form lying outside and adjacent the back of said reflector with its axis parallel to the focal axis of said reflector, a pair of balanced lines extending parallel to each other and radially from said convertor, and a pair of coplanar sheet radiator elements connected to and supported by said balanced lines respectively, said sheet radiator elements being of generally triangular form, with their bases parallel and adjacent each other at the points of connection to said balanced lines.

6. A broad band antenna comprising a line balance convertor of generally cylindrical form, with an unbalanced line extending along the axis of said convertor and a pair of balanced lines extending parallel to each other and radially of said convertor, and a pair of radiator elements connected to and supported by said balanced lines respectively, said radiator elements comprising coplanar sheets of conductive material, each of generally triangular form, with their bases parallel and adjacent each other at the points of connection to said balanced lines.

7. A doublet antenna structure including a pair of coplanar flat sheets of conductive material, each of generally isosceles triangular form, with their bases parallel and adjacent each other, and a pair of transmission lines connected to said sheets respectively at said bases.

8. An antenna structure including at least one pair of coplanar flat sheets of conductive material, each of approximately isosceles triangular form, with their bases parallel and adjacent each other, at least one reflector and a pair of transmission lines connected to said sheets respectively at said bases.
